FIG. 1

FIG. 3

FIG. 2

FIG. 4

FIG. 5

FIG. 6

FIGURE 1 is a top plan view of a combined bottle and top cover showing my new design;

FIGURE 2 is a front elevational view, the opposite side being a mirror image of the side shown;

FIGURE 3 is an elevation view looking from the right of FIGURE 2, the opposite side being the same in appearance except for the appearance at the end of the strap and the buckle element;

FIGURE 4 is a vertical sectional view taken on the line 4-4 of FIGURE 2, the upper portion of the bottle being illustrated in elevation and a portion being broken away for convenience of illustration;

FIGURE 5 is a vertical sectional view taken on the line 5-5 of FIGURE 3, the upper portion of the bottle being illustrated in elevation and a portion being broken away for convenience of illustration; and

FIGURE 6 is a perspective view of the top cover detached.

I claim:

The ornamental design for a combined bottle and top cover, as shown and described.
